UNITED STATES PATENT OFFICE.

OLOF OHLSON, OF WEST NEWTON, MASSACHUSETTS, ASSIGNOR TO GILBERT J. McCARTHY, OF WASHINGTON, DISTRICT OF COLUMBIA.

PROPELLER.

Application filed August 26, 1925. Serial No. 52,607.

This invention relates to improvements in propellers and particularly in the structural arrangement thereof.

An object of the invention resides in providing a propeller structure conformed of a plurality of blade sections of members which have hub portions adapted for interfitting connection to mount the blades in assembled propeller forming relation.

10 A further object of the invention resides in providing a propeller structure wherein the blades and the entire structure is adapted to be manufactured from strip material so that a plurality of radially arranged blades may 15 be provided with hub portions adapted for interfitting connection to form a rigid assembled propeller structure.

The invention comprehends a novel construction of propeller having numerous advantages which are particularly pointed out in the following description and in the claims directed to a preferred form of the invention, it being understood however, that various changes may be made in the size, 25 shape and relation of the parts without departing from the spirit or scope of the invention as herein set forth.

In the drawing forming part of this application

30 Figure 1 is an end elevation of the improved novel propeller construction.

Fig. 2 disassembled perspective view of the blade sections adapted for interfitting connection to form a completed propeller.

35 The novel propeller construction forming the subject matter of this invention includes a plurality of independent blade sections and in the present case, two blade sections are shown indicated by the numerals 1 and 2 respectively. These blade sections include the radial blades 3, the base portions of which extend axially of the hub portion of the propeller as indicated by the numeral 4, while the ends of the blades are twisted out 45 of the axial plane so that they will be rotated by or direct a current of air axially relative to said propeller.

These blades are formed of strip material and having hub portions 5 formed as an integral part thereof joining the blades 3 at the base portions 4. In the form of the invention illustrated in the drawing, the hub portions 5 are formed of arcuate portions 6 extending from the base portion 4 of the 55 blades, of substantially semi-circular form

from which the remaining part of the end portion is offset as indicated at 7 while a reduced semi-circular portion 8 extends from this offset portion in concentric relation to the portion 6 and in opposed relation thereto.

At the end of the semi-circular portion 8 is formed another offset portion 9 from which extends a third arcuate portion 10 in adjacent spaced relation to the portion 6 and concentric relative thereto.

As shown in Fig. 2 of the drawing, all of the blade sections are of identical construction and when placed in the position shown in Fig. 2, they will slidably interfit to form a complete propeller structure as illustrated in Fig. 1, in which the portions 6, 8 and 10 have interfitting relation and closely contact with one another to form a complete solid propeller hook and at the same time preventing circumferential movement of the blades and hub sections relative to one another so that a rigid structure results. It is to be particularly noted that the entire propeller structure is formed of strip material and that the offset portions 7 and 9 are sufficient to space the semi-circular portions 6, 8 and 10 inwardly in stepped relation equal to the thickness of the strip material from which the sections are formed.

It is to be further noted from an inspection of Fig. 1 that the bearing surface on the interior of the hub portion is provided partly in each of the blade sections and that the same is of substantially true cylindrical form from which the blades extend in radial relation.

It is also to be further noted that the interfitting relation produced prevents circumferential movement between the blade sections due to the interfitting relation of the offset portions 7 and 9 respectively.

From the foregoing description it will be readily apparent that a substantially simple and yet highly practical propeller construction has been provided which may be manufactured of strip material which is adapted for use in the manufacture of numerous types of small size propellers such as for fans, gas mixers and the like.

Having thus described my invention, what I claim as new is:—

1. A propeller comprising a plurality of blade sections formed of strip material having hub portions formed on one end thereof

- including a plurality of arcuate concentric interconnected sections adapted for slidable interfitting connection in propeller forming relation.
- 6 2. A propeller comprising a plurality of independent blade sections having mating interfitting hub forming sections including means providing self locking cooperation in propeller forming relation.
- 10 3. A propeller comprising a plurality of blade sections having hub portions formed on one end for concentric slidable interfitting relation.
- 15 4. A propeller comprising a plurality of blade sections having hub portions formed for concentric slidable interfitting relation,
- and means formed on said hub portions to provide self locking between the sections in assembled relation.
5. A propeller comprising a plurality of 20 blade sections formed of strip material having hub portions formed on one end thereof including a plurality of concentric interconnected sections adapted for slidable interfitting connections in propeller forming relation, and means formed at the juncture of 25 said inner connected concentric sections for providing self locking cooperation of the blade sections.

In testimony whereof I affix my signature.

OLOF OHLSON.
